UNITED STATES PATENT OFFICE.

MICHAEL W. McCARDLE, OF CHICAGO, ILLINOIS.

SHEEP-SHEAR BLADE.

Application filed January 31, 1927. Serial No. 164,706.

The purpose of this invention is to provide an improved construction of a cutting blade for a sheep shear and the like tools, adapted for rendering the blade reversible for utilizing the shear edges of the teeth at both surfaces of the blade and also in the preferred form for utilizing shear teeth formed at both longitudinal edges of the blade.

10 In the drawings:

Figure 1 is a plan view of a cutter blade embodying this invention in one of its forms.

Figure 2 is a section at the line, 2—2, on Figure 1.

15 Figure 2^a is a section at the same line, showing one piece formation.

Figure 3 is a plan view of a modified and in some respects preferred form of the blade embodying the invention.

20 Figure 4 is an end edge elevation of the blade shown in Figure 3.

Figure 5 is a section at the line, 5—5, on Figure 3.

In both the forms shown in the drawings

25 A represents the vibrating cutter of a sheep shear and the like tool, provided with means for its engagement by the actuating lever of the tool for vibrating it, said means consisting in the apertures, *a*, for engagement

30 of the cooperating projections on the vibratory lever of well known construction (not shown).

The characteristic of the invention consists in the form of the cutting edges of the blade which is produced by recessing said edges over their entire operating length between the opposite upper and lower surfaces of the blade for forming acute angled cutting corners of the blade. The recesses in the edge of the blade are indicated at 10

40 at the several edges shown in the drawings.

Preferably the recess is symmetrical with respect to the two opposite surfaces of the blade between which it is formed, as seen in the drawings, and preferably also said recess

45 is angular as shown in the drawings.

The advantage and purpose of this feature of construction will be recognized as being the adaptation of the blade to be used either side up on the comb or co-operating shear member of the tool for performing its shearing function by means of either corner of the shearing edge, both edges being alike in respect to their capacity for shearing, and the cutting teeth being formed as to the slope 50 of their converging edges for co-operating similarly and equally with the teeth of the

comb or fixed cutter of the tool; so that the blade may be ground in the usual manner alike upon the two faces and being originally ground for sharpening the cutting corners 60 upon both faces, the tool may be continued in use twice as long without interrupting for regrinding as if it could not be used either side up, as the construction described renders 65 possible.

The blade as thus far described may be formed as to the recessed edges by milling and grinding the edges with properly formed milling and grinding tools, from a single piece of metal plate of suitable thickness for receiving the grooves or recesses in its edges; but the preferable mode of construction best adapted for economical and accurate production consists in making the blade of two plates or laminae perfectly 70 matched at their meeting faces and as to outline, each plate being beveled at the side of the meeting face before the plates are secured together, the two bevels co-operating 75 to form the recess when the plates are thus 80 matched and secured face to face. The desirable method of securing the plates together is by electric welding, as may be understood from the drawings not showing riveting or other visible means of secure- 85 ment.

I claim:—

1. A vibrating cutter blade for a sheep shear and the like, consisting of a metal plate of uniform thickness throughout, 90 whereby the opposite faces are in parallel planes, having teeth projecting from a longitudinal edge and recessed between said opposite parallel faces throughout the operating length of the shearing edges of said 95 teeth.

2. A vibrating cutter for sheep shear and the like, consisting of a metal plate of uniform thickness throughout, having its cutter teeth distributed symmetrically about a fore-and-aft middle line, whereby it is adapted to be reversed longitudinally to bring either of said opposite surfaces into co-operation with the other member of the shear, and having the cutting edges of the teeth recessed throughout their operating length between said two opposite faces. 100 105

3. A vibrating cutter blade for sheep shear and the like, consisting of a metal plate of uniform thickness, whereby its opposite surfaces are in parallel planes, said blade having teeth projecting oppositely 110

from its opposite longitudinal edges and distributed symmetrically about a fore-and-aft middle line and also about a longitudinal middle line, whereby the blade is adapted to be reversed both end-for-end and surface-for-surface, the teeth upon both longitudinal edges being recessed between the opposite surfaces over their entire operating length to form acute angled cutting corners at both said surfaces.

4. A vibrating cutter blade for a sheep shear and the like consisting of a metal plate of uniform thickness throughout, whereby the opposite faces are in parallel planes, having teeth projecting from a longitudinal edge recessed between said opposite parallel faces throughout the operating length of the

shearing edges of said teeth, said recesses being symmetrical with respect to said opposite faces.

20

5. A vibrating cutter blade for a sheep shear and the like, consisting of a metal plate of uniform thickness throughout, whereby the opposite faces are in parallel planes, having teeth projecting from a longitudinal edge angularly recessed between said opposite parallel faces throughout the operating length of the shearing edges of said teeth.

In testimony whereof, I have hereunto set my hand at Chicago, Illinois, this 27th day of January, 1927.

MICHAEL W. McARDLE.
